CLAIM

The ornamental design for a dispenser gun, as shown and described.

DESCRIPTION

FIG. 1 is a rear and left side perspective view of a dispenser gun, showing my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The features shown in broken lines in FIG. 7 depict portions of the dispenser gun that form no part of the claimed design.
